Primary Examiner — Catherine Tuttle(74) *Attorney, Agent, or Firm* — Gifford, Krass, Sprinkle, Anderson & Citkowski, P.C.; Mark D. Schneider(57) **CLAIM**

I claim the ornamental design for a studded ball, as shown and described.

DESCRIPTION

FIG. 1 is a right side elevation view of the studded ball showing my new design, the opposing left side view being identical thereto;

FIG. 2 is a front elevation view thereof, the opposing end view being identical thereto; and,

FIG. 3 is a perspective view thereof.
